DESIGN FOR A GLOVE

Irwin Steinberger, New York, N. Y., assignor to Aris Gloves, Inc., New York, N. Y., a corporation of California

Application March 10, 1938, Serial No. 75,740

Term of patent 3½ years

To all whom it may concern:

Be it known that I, Irwin Steinberger, a citizen of the United States and a resident of New York city, in the county of New York and State of New York, have invented a new, original, and ornamental Design for a Glove, of which the following is a specification, reference being had to the accompanying drawing, forming part thereof.

The characteristic feature of my design resides in the specific stitching on the back of the glove in combination with the stitching across the palm of the glove, as shown.

I claim:

The ornamental design for a glove, substantially as shown and described.

IRWIN STEINBERGER.
